UNITED STATES PATENT OFFICE

2,466,848

ADJUSTABLE PANEL FOR CABINET DOORS

Robert R. Hausner, Chicago, Ill.

Application June 14, 1946, Serial No. 676,781

1 Claim. (Cl. 312—189)

1

This invention relates to an adjustable mirror or other panel and more particularly to such a member positioned on the front of a bathroom medicine cabinet, or the like.

A primary object of this invention is the provision of such a member positioned on an enclosure having a hinged door, as for example, a bathroom medicine cabinet, provided with means whereby the relative height of the mirror may be varied to accommodate a variety of purposes, such as use by a small child, or adults of varying height.

An additional object of the invention is the provision of such a device which may be readily and simply moved with a minimum of effort and difficulty to any desired height.

A further object is the provision of such a device which may be readily adapted for use with any conventional medicine cabinet having a flanged door.

Still other objects reside in the combinations of elements, arrangements of parts, and features of construction, all as will be more fully pointed out hereinafter, and shown in the accompanying drawings, wherein there is disclosed a preferred embodiment of this inventive concept.

In the drawings:

Figure 1 is a front elevational view of the adjustable mirror of the invention as applied to a cabinet, an alternative position of adjustment being indicated in dotted lines.

Figure 2 is a side elevational view of the construction shown in Figure 1, an alternative position of adjustment being indicated in dotted lines.

Figure 3 is a top plan view of the structure shown in Figures 1 and 2.

Figure 4 is an enlarged fragmentary sectional view taken substantially along the line 4—4 of Figure 1, as viewed in the direction indicated by the arrows.

Similar reference characters refer to similar parts throughout the several views of the drawings.

Referring now to the drawings, there is generally indicated at 10 a medicine cabinet of any desired conventional type, having hingedly secured to the front thereof, as by means of hinges 11, a door 12, having outer edges 13, extending a substantial distance beyond the edges of the cabinet 10.

The adjustable mirror of the instant invention comprises a mirror 14, provided about its edges with a molding 15, which molding is provided with flanges 16 on the sides thereof, which in turn have additional flanges 17 at right angles thereto, the flanges 16 and 17 forming channels adapted

2

to surround the extending edges 13 of the door 12. Thus, it will be seen that the mirror 14 is slidable vertically with respect to the door 12.

Means are provided for securing the mirror in adjusted position, and take the form of spring clips members generally indicated at 18, and each including a resilient leaf spring 19 secured, as by a screw 20, to the flange 17. The spring members 19 are outwardly flared at their end portions, as at 21, and provided with an extending pin or tooth 22 which passes through an aperture 23 in the flange 17, into a selected one of a plurality of aligned holes 25 in the door 12. An extending finger portion 26 is provided on the spring member 19 and the arrangement is such that pressure on the member 26 serves to lift the finger 22 out of its associated aperture 25 permitting sliding movement of the mirror with respect to the door.

Obviously, any desired number of apertures 25 may be provided in substantially horizontal alignment on opposite sides and vertically aligned on the flange 13, in such manner that the mirror may be adjusted vertically to any one of a plurality of desired positions.

25 Now, from the foregoing, it will be seen that there is herein provided a device which accomplishes all the objects of this invention, and others, including many advantages of great practical utility and commercial importance.

30 As many embodiments may be made of this inventive concept, and as many modifications may be made in the embodiment hereinbefore shown and described, it is to be understood that all matter herein is to be interpreted merely as illustrative and not in a limiting sense.

I claim:

35 A cabinet, a front door hinged to the cabinet and having marginal vertical edges projecting beyond the cabinet, one vertical marginal edge of the door having longitudinally spaced openings, a vertically adjustable sheet arranged upon the front face of the door and having vertical channel-flanges formed upon its vertical edges slideably receiving the vertical edges of the door, 40 the channel-flanges including inner channel sides, one channel side having a transverse opening, a leaf spring arranged upon the rear face of the channel side and attached thereto and provided at its free end with a lock tooth entering the transverse opening of the inner channel side and adapted to enter a selected opening in the door, 45 and a lever attached to the leaf spring near its free end and extending longitudinally toward the attached end of the leaf spring and spaced from such attached end, the arrangement being such

that when the free end of the lever is pressed toward the adjacent inner channel side the lock tooth will be moved outwardly with respect to the opening in the door.
